ANTI-ICING GASOLINE

William E. Lovett, Scotch Plains, Raymond W. Walker, Union, and John M. Jordan, Plainfield, N.J., assignors to Esso Research and Engineering Company, a corporation of Delaware

No Drawing. Filed Feb. 27, 1958, Ser. No. 717,829

1 Claim. (Cl. 44—56)

The present invention relates to improved fuels for use in spark-ignition internal combustion engines and more particularly, relates to improved gasolines inhibited against carburetor icing during cool, humid weather by the incorporation therein of minor amounts of a synergistic mixture of a low boiling aliphatic alcohol and a primary amino alkanol.

The problem of carburetor icing and the engine power losses and stalling which result therefrom is not a new one. Operators of automotive, aviation, marine and stationary gasoline engines, particularly those in the colder areas of the United States, have long been familiar with the problem. Tests and surveys have shown that most engines are subject to carburetor icing when the atmospheric temperature ranges from about 30 to about 60° F. and when the relative humidity is in excess of about 65%. Such icing is not confined to any particular type of engine or to any particular type of carburetor. When a gasoline engine is first started, the engine carburetor is immediately chilled to a temperature considerably below the atmospheric temperature due to the refrigerating effect of the vaporizing gasoline. This reduced carburetor temperature, often as much as 50° F. below the atmospheric temperature, persists beyond the warm-up period for the rest of the engine because of the external position of the carburetor and the poor heat transfer to it. On a humid day, moisture in the air entering the carburetor condenses and freezes on the throttle plate and the carburetor walls adjacent thereto. Such freezing occurs most readily during conditions of light-load operation. When the throttle is closed to the idle position, ice which has formed on the throttle plate and adjacent carburetor walls, plus ice which then forms, restricts the flow of air into the engine. The result is a loss of engine power and frequently the engine stalls. The problem is particularly aggravated in the case of engines equipped with carburetors having venturi diameters on the order of 21 mm. or less and is also more severe in engines having the venturi tube insulated from the carburetor body. Many gasoline engines are equipped with carburetors having these features.

In recent years the problem of carburetor icing and engine stalling has become more severe, particularly with respect to automobile engines. Most late model cars have automatic throttles and therefore drivers are no longer able to increase the engine idling speed during the warm-up period in order to prevent stalling. Moreover, modern automobiles having automatic transmissions have idling speeds which are rather critical during the warm-up period. The fastest idling speed which can be tolerated without creeping of the car is often too low to prevent stalling of the engine.

Another factor which has made the problem of carburetor icing more serious in recent years is the volatility of the gasolines now marketed. Tests have shown that a wholly hydrocarbon fuel having volatility such that the ASTM 50% distillation point by method D-86 is above about 310° F. is not subject to stalling during warm-up.

2

Present day fuels are considerably more volatile than this. ASTM specifications now permit a maximum 50% distillation point of 284° and most commercial gasolines have 50% distillation points somewhat below the allowable ASTM maximum. These highly volatile modern gasolines give rise to carburetor icing and stalling difficulties much more frequently than the older, less volatile fuels.

The present invention provides an improved class of 10 gasolines inhibited against carburetor icing and consequent stalling by the incorporation therein of a mixture of a low boiling aliphatic alcohol and a primary amino alkanol. In accordance with the invention, it has now been found that these materials in combination exhibit a synergistic 15 effect and give considerably greater protection against carburetor icing than either component alone. Considerably lower concentrations are thus made possible by the invention. In addition, the presence of the low boiling aliphatic alcohol considerably improves the solubility of the primary amino alkanol in gasoline at low temperatures and reduces the water extractability of the primary amino 20 alkanol. This results in a fuel which is more stable than those employing the primary amino alkanol as the sole anti-icing agent. The additives of the invention have the 25 additional advantage in that they prevent rusting and corrosion which often takes place due to the presence of small quantities of water in gasoline.

The primary amino alkanols which are used in the 30 gasolines of the present invention have the generic formula:

35 where R is an alkyl radical having from 1 to 3 carbon atoms, n is zero to one and R' is selected from the group consisting of hydrogen and alkyl groups containing from 1 to 2 carbon atoms; wherein the amino group is a primary amino group attached to a tertiary carbon atom; and wherein the total number of carbon atoms ranges from about 4 to about 9, preferably from about 4 to about 6. The compounds represented by this formula are primary-amino, tertiary-alkyl carbinols. The alkyl groups 40 can be methyl, ethyl, propyl or isopropyl groups. A particularly preferred primary amino alkanol for use in accordance with the invention is 2-amino-2-methyl-1-propanol.

45 The low boiling alcohols employed in the fuels of the invention are those containing from 2 to 5 carbon atoms per molecule and include ethanol, propanol, isopropanol, butanol, isobutanol and the like. Isopropanol has been found to be particularly effective in the improved gasolines of the invention and therefore is preferred.

50 The primary amino alkanol and the low boiling aliphatic alcohol are employed in the fuels of the invention in concentrations such that the fuels contain from about 0.001 to about 0.4% by volume of the primary amino alkanol and 0.4 to about 2.5% by volume of the aliphatic alcohol. Concentrations of from about 0.05 to about 0.1% by volume of primary amino alkanol and concentrations of about 0.75 to about 1.25% by volume of the low boiling aliphatic alcohol are preferred. It is also preferred to employ the additive constituents in concentrations such that the ratio of the concentration of the aliphatic alcohol and the concentrations of the primary amino alkanol ranges from about 40 to 1 about 5 to 1.

55 Gasolines as contemplated for use in accordance with the present invention have been defined broadly by the American Society for Testing Materials as "complex mixtures composed almost entirely of relatively volatile

hydrocarbons which vary widely in their chemical and physical properties." Such gasolines are derived from petroleum by a variety of refining processes including fractional distillation, catalytic cracking, hydroforming, alkylation, polymerization, solvent extraction and the like. They include aromatics, naphthenes, olefins, paraffins and sometimes diolefins. They may be used as fuels for aviation engines, marine engines and stationary engines. Gasoline normally boils between about 80° F. and about 450° F. when tested by ASTM method D-86. Its vapor pressure by ASTM method D-323 varies from about 6 to about 15 pounds per square inch or higher at 100° F., depending on the particular season of the year during which it is to be used. The additive materials of the invention are of particular application to gasolines having vapor pressures in the upper part of this range, i.e. between 9 and 15 pounds per square inch. The gasolines in which the additive materials of the invention are used may have octane ratings ranging from about 83 up to about 104 or higher. Such gasolines normally contain at least 2 cc. of tetraethyl lead per gallon and a halohydrocarbon scavenger agent in concentrations of about 1.0 to 2.0 theories.

The gasolines in which the additive materials of the invention are incorporated may also contain other additive materials. Examples of such additive materials include solvent oils consisting of hydrocarbon mixtures having a Saybolt viscosity at 100° F. not above 450 seconds, a 50% distillation point above about 350° F. at 10 millimeters of mercury pressure, and an API gravity between about 18 and 28°; corrosion inhibitors such as Santolene C, which is a phosphorus-containing dimer of linoleic acid, amines and amine phosphates and nitrites; gum inhibitors such as N,N'-dissecondary butyl p-phenylene diamine, 2,4-dimethyl-6-tertiary butyl phenol and 2,6-di-tertiary butyl-4-methylphenol; dyes such as 1,4-diisopropyl aminoanthraquinone and p-dimethyl aminoazobenzene; dye stabilizers such as ethylene diamine; and similar additive materials commonly used in gasolines. The gasolines of the invention will, however, comprise at least 95% by weight of hydrocarbons.

The invention can be more fully understood by reference to data set forth in the following examples.

EXAMPLE 1

Tests were carried out to determine the carburetor icing characteristics of a premium grade leaded motor gasoline with and without the additive materials of the invention. The gasoline had the following inspections:

Reid vapor pressure	lbs./sq. in	13.5
Initial boiling point	° F.	90
5% point	° F.	105
10% point	° F.	117
50% point	° F.	190
90% point	° F.	295
95% point	° F.	338
Final boiling point	° F.	351

Samples of this gasoline were blended with small amounts of a low boiling aliphatic alcohol, a primary amino alkanol, and mixtures of the low boiling alcohol and alkanol. These samples were then tested in a 1956 Plymouth engine by starting the engine, operating it for a period of 30 seconds at 1500 revolutions per minute, and then permitting the engine to idle for 15 seconds. This procedure was repeated 25 times, the engine being cold at the beginning of each test series. The number of stalls which occurred in each series of tests was noted and taken as an indication of the carburetor icing characteristics of the fuel being tested. The data were obtained at an atmospheric temperature of 40° F. and at 100% relative humidity. The results of this test are shown in the following table.

Table I
ANTI-ICING EFFECT OF ADDITIVES

	Fuel	Average number of stalls in 25 cycles
Base gasoline ²		18
Base gasoline plus 1.0% isopropanol		14
Base gasoline plus 2.0% isopropanol		7.5
Base gasoline plus 0.05% 2-amino-2-methyl-1-propanol		11
Base gasoline plus 0.1% 2-amino-2-methyl-1-propanol		7.8
Base gasoline plus 0.05% 2-amino-2-methyl-1-propanol plus 1.0% isopropanol (expected)		7
Base gasoline plus 0.05% 2-amino-2-methyl-1-propanol plus 1.0% isopropanol (found)		5

¹ Data were obtained with a 1956 Plymouth test car operated at a temperature of 40° F. and 100% relative humidity.

² Base gasoline was a premium winter grade gasoline having a Reid vapor pressure of 13.5 p.s.i. and an ASTM 50% distillation point of 190° F.

From the above data it can be seen that the mixture of the low boiling saturated aliphatic alcohol and the primary amino alkanol gave a lower number of stalls than occurred when the individual constituents were used. The reduction in stalls was not merely an additive one but instead was clearly synergistic, the number being lower than that which would be predicted upon the basis of the individual constituents.

EXAMPLE 2

Primary amino alkanols have excellent anti-icing properties. Their physical properties, however, limit their usefulness as gasoline additive agents. They have extremely low solubility in gasoline at the temperatures which are often encountered in aviation fuel tanks at high altitudes and in automobile gasoline tanks during the winter. In order to demonstrate the improved properties which result when such primary amino alkanols are used in conjunction with low molecular weight aliphatic alcohols, a series of tests was carried out in which the solubility of 2-amino-2-methyl-1-propanol in gasoline containing various amounts of isopropanol was determined at -20° F. The results of these tests are summarized in Table II below.

Table II
EFFECT OF LOW MOLECULAR WEIGHT ALCOHOLS UPON SOLUBILITY OF PRIMARY AMINO ALCOHOL

	Fuel	Solubility of 2-amino-2-methyl-1-propanol in fuel at -20° F., percent
Base gasoline ¹		0.01
Base gasoline plus 0.6% isopropanol		0.05
Base gasoline plus 0.8% isopropanol		0.10
Base gasoline plus 1.0% isopropanol		0.30

¹ Base gasoline was a premium winter grade gasoline having a Reid vapor pressure of 13.5 p.s.i. and an ASTM 50% distillation point of 190° F.

It can be seen from Table II that while the solubility of 2-amino-2-methyl-1-propanol in gasoline is only 0.01 volume percent at -20° F., the presence of 1% isopropanol increases solubility of the primary amino alkanol to 0.3%. This increase in solubility at low temperature is significant because it provides a method for preventing the separation of the primary amino alkanol from the gasoline at a low temperature and thus assures that the anti-icing properties contributed by the alkanol are not lost at high altitudes or during severe winter weather.

Ethanol and other low boiling aliphatic alcohols have been found to affect the solubility of the primary amino alkanol in the manner shown for isopropanol in the above table.

EXAMPLE 3

Because of the water solubility of primary amino alkanols, they are often extracted from gasolines stored

for prolonged periods. In accordance with the invention it has been found that in addition to the benefits shown above, the presence of a low boiling aliphatic alcohol decreases the water extractability of the primary amino alkanols. Tests were carried out in which gasolines containing 2-amino-2-methyl-1-propanol were mixed with water, in the presence and in the absence of isopropanol, and the distribution of the primary amino alkanol between the water and the gasoline phases was determined. The tests were carried out at temperatures of from 70 to 80° F. The data obtained are shown in Table III below. These tests were intentionally more severe than the conditions that would normally be encountered in commercial storage and use of gasoline.

Table III

EFFECT OF LOW MOLECULAR WEIGHT ALCOHOLS UPON WATER EXTRACTABILITY OF PRIMARY AMINO ALKANOLS FROM GASOLINE

Fuel	2-amino-2-methyl-1-propanol in gasoline phase, vol. Percent	2-amino-2-methyl-1-propanol in water phase, vol. Percent	Equilibrium Constant—Eq. conc. in water/eq. conc. in gasoline
Base gasoline ¹	0.05	34	680
Base gasoline+0.75 vol. percent isopropanol.....	0.05	24	480
Base gasoline ¹	0.1	58	580
Base gasoline+0.75 vol. percent isopropanol.....	0.1	44	440

¹ Base gasoline was a premium winter grade gasoline having a Reid vapor pressure of 13.5 p.s.i. and an ASTM 50% distillation point of 190° F.

Although the concentration of isopropanol used in the tests reported in the above table was only 0.75 vol. percent, it can be seen from the table that the amount of the 2-amino-2-methyl-1-propanol in the water phase was considerably reduced. Greater concentrations of isopropanol or a similar low molecular weight aliphatic alcohol would reduce the equilibrium constant to an even greater extent.

EXAMPLE 4

To demonstrate the rust inhibiting effect of the additive compositions of the invention, metallic strips were suspended in a gasoline similar to that employed in Example 1 containing a minor amount of water. To a sample of the same gasoline a very small amount of a mixture of isopropanol and 2-amino-2-methyl-1-propanol

was added and a similar metal strip was suspended in this fuel. The amount of rust which had occurred at various intervals was noted and is shown in Table IV.

Table IV

Fuel	Rusting after indicated time				
	7 days	9 days	23 days	36 days	65 days
Base gasoline ¹	Trace	Trace	M	Heavy	Heavy
Base gasoline+2.0 vol. percent isopropanol+0.001 vol. percent 2-amino-2-methyl-1-propanol.....	None	None	None	None	Slight

¹ Base gasoline was a premium winter grade gasoline having a Reid vapor pressure of 13.5 p.s.i. and an ASTM 50% distillation point of 190° F.

The data of Table IV show that the additive materials of the invention are quite effective for inhibiting rust as well as for reducing carburetor icing.

EXAMPLE 5

An anti-stalling gasoline in accordance with the invention has a Reid vapor pressure of 9 p.s.i. and an ASTM 50% distillation point of 210° F. and contains 2.0% ethanol, 0.3% 2-amino-2-methyl-propanol-1, 3 cc./gal. of tetraethyl lead, 1.0 theories of ethylene dichloride, 0.5 theories of ethylene dibromide, 1.0% of a light neutral solvent oil having a Saybolt viscosity at 100° F. of 380 seconds and 15 pounds of N,N'-disubstituted butyl p-phenylene diamine per thousand barrels.

What is claimed is:

A gasoline to which has been added about 0.4 to about 2.5 vol. percent of isopropanol and about 0.001 to about 0.4 vol. percent of 2-amino-2-methyl-1-propanol.
